UNITED STATES PATENT OFFICE.

WALTER STOCK, OF ALBANY, NEW YORK.

DEVICE FOR UPSETTING OR LENGTHENING AN IRON BAR.

1,117,611.

Specification of Letters Patent.

Patented Nov. 17, 1914.

Application filed May 15, 1913. Serial No. 767,767.

To all whom it may concern:

Be it known that I, WALTER STOCK, a citizen of the United States of America, residing at the city of Albany, in the county of Albany and State of New York, have invented certain new and useful Improvements in Devices for Upsetting or Lengthening an Iron Bar, of which the following is a specification.

My invention relates to devices for upsetting or lengthening an iron bar, and the object of my invention is to provide a means for applying force to the end of a side rod, pedestal binder or other piece of iron while it is held securely in position, and thereby shortening it, which device may also be arranged in such a manner that the force applied to the end of the piece operated on will cause it to be lengthened by stretching it forward while it is held securely along the sides; together with such elements and combinations as are hereinafter more particularly set forth and claimed.

I accomplish these objects by means of the mechanism illustrated in the accompanying drawing, in which:

Figure 1 is a section along the line 1—1 on Fig. 2. Fig. 2 is a plan. Fig. 3 is a detail side elevation, with parts broken away, showing the means for connecting the dial finger with the plunger. Fig. 4 is a section along the line 2—2 on Fig. 2. Fig. 5 is a plan showing a piece of iron placed in position for being shortened. Fig. 6 is a plan showing a piece of iron in position for being lengthened. Fig. 7 is a side elevation, partly in section, of the device with piece of iron as in Fig. 6.

Similar letters refer to similar parts throughout the several views.

It is often necessary to shorten or upset a binder or side rod, or other piece of heavy iron, especially in a railway car repair shop, and it is necessary to keep the rod, binder or other bar straight without being curved or bent at the end, which is liable to occur after the bar has been heated and it is pounded or submitted to blows for the purpose of reducing its length. I have arranged a device by means of which the iron bar is securely gripped and positively held against a steady force exerted preferably by means of a hydraulic jack, screw or similar arrangement applied at one end of the bar.

In order to accomplish this result, I provide

a frame, A, on the upper surface of a portion of which I form the groove, B, and through a wall, C, in the frame and on a line with the bottom of the groove, B, I reciprocate the ram, D. In the chamber, E, of the frame I place the toggle, F, beneath the connecting links of which toggle, F, I place, preferably, a hydraulic jack, G. On each side of the groove, B, and near one end thereof I place the cam-shaped gripping blocks, H, H. These cam-shaped blocks are so arranged that when an iron bar is placed in the groove, B, the blocks may be made to engage the sides of the bar and any movement of the bar will tend to force the blocks 65 tighter and make the bite of the blocks into the bar sharper and deeper. In the upper surface of a part of the frame, A, I also provide a groove, J, which is in alinement with, although, preferably, the bottom of this groove is of less altitude than the groove, B, and is provided along its sides with the grooves, b, to permit of the reciprocation of the lateral projections, n, at the bottom of the block, K. In the groove, J, I place a 70 sliding block, K, which is provided at each side with a cam gripping block, L, similar to the gripping blocks, H, H, and in the bottom of the groove, J, I place a series of holes, M, through which a bolt, N, may be placed 75 behind the block, K, and prevent the block from moving toward the rear end of the groove, J. The projections, n, at the bottom of block, K, sliding in the grooves, b, keep the block in the frame as against any tendency to rise out of the frame during the application of pressure to the work. As thus arranged, when an iron bar W suitably heated is placed in the groove, B, with its end 80 against the block, K, and the bolt, N, placed 85 through one of the openings, M, and the ram, D, against the end of the bar, when force is applied to the toggle, F, the bar W may be upset without bending, curving or interfering with the operating shape of the 90 end of the bar.

When it is desired to lengthen the bar W, it is placed on the block, K, and in engagement with the gripping blocks, L, and also in engagement with the gripping blocks, H, H. An iron rod, X, is placed between the ram, D, and the block, K, as shown in Figs. 6 and 7, and then force is applied to the toggle, and as the block, K, is moved in the groove, J, the bar W will be drawn out or 105 110

lengthened. It is apparent that in doing this the bar is not injured or its shape or form changed. The tightly gripping blocks, H, H, and L, L, hold the sides of the bar W firmly and the constant and irresistible pressure applied by the jack stretches or moves out the bar because of the block, K, being movable in the groove, J.

For the purpose of straightening or bending a bar it may be placed transversely of the frame, A, between the pair of gripping blocks, H, H, and L, L, the block, K, being held by the bolt, N, and the iron rod, X, placed in the groove, B, resting against the bar to be bent, which may be acted upon by the ram, D.

I have shown in Fig. 3 a means for showing just how far to move the ram, D, which should of course indicate when the bar has been upset or lengthened the predetermined amount. This is done by means of a dial, O, with a finger, P, pivoted to the lower part, p, of the dial and the end of the finger attached to the link, R, which is secured to the ram, D, by means of a screw, d, movable in the slot, r. By moving the finger to the zero point after the hydraulic jack has taken up the lost motion and is ready to operate upon the end of the bar, then after pressure is applied a reading of the dial will show how far the ram has been projected. Or the finger on the dial may be placed so as to show just how much it is desired to shorten or lengthen the bar of iron, and by watching the dial until the

finger reaches that point the jack may be stopped.

I do not wish to limit myself to the use of a hydraulic jack, as any means for applying force to the toggle comes within the spirit of my invention.

What I claim as my invention and desire to secure by Letters Patent is:

1. A machine of the class described comprising a frame provided with a groove into which a bar to be operated on may be placed; an adjustable block placed in said frame against which one end of said bar may engage; means for holding said block against pressure exerted through said bar; a ram adapted to engage the end of said bar opposite that which is in engagement with said block; a toggle connected with said ram; and means for operating said toggle. 55

2. A machine of the class described, comprising a frame; a ram; a toggle for operating said ram; means for operating said toggle; a movable block; a pair of oppositely disposed cam-shaped gripping blocks on said frame; and a pair of oppositely disposed cam-shaped gripping blocks on said block; substantially as described.

In testimony whereof I have affixed my signature in presence of two witnesses.

WALTER STOCK.
